UNITED STATES PATENT OFFICE.

JOSEPH L. COX, OF BATTLECREEK, MICHIGAN, ASSIGNOR TO DUPLEX PRINTING PRESS COMPANY, OF SAME PLACE.

PRINTING-PRESS.

SPECIFICATION forming part of Letters Patent No. 680,128, dated August 6, 1901.

Application filed August 10, 1895. Serial No. 558,916. (No model.)

To all whom it may concern:

Be it known that I, JOSEPH L. COX, of Battlecreek, in the county of Calhoun and State of Michigan, have invented certain new and useful Improvements in Printing-Presses; and I do hereby declare that the following is a full, clear, and exact description thereof, reference being had to the accompanying drawings, and to the letters of reference marked thereon, which form part of this specification.

My present invention pertains to a flat-bed type-printing web-perfected press in which the paper is automatically fed and taken care of from a web-roll supply and the perfected impressions thereupon are made by a compound printing-press employing a pair of locomotive reciprocating impression-cylinders operating forward and backward over a pair of reciprocating type-beds which are moved or traveled in opposite directions to the travel or reciprocations of the impression-cylinders, the principal object being to shorten the travel of heavy parts in this class of presses, and consequently to increase the product therefrom.

The present invention is different from my web-perfected press of a similar character patented May 14, 1895, No. 539,356, inasmuch as the present structure operates to print and perfect sheets upon a web and sever them after printing, while in the press shown in said patent, though employing traveling cylinders and traveling beds and operating to print and perfect from a web-roll supply, does so by first severing the sheets and then printing them.

The general construction, arrangement of parts, and operation of the mechanisms of the present application are similar to that of the flat-bed web-perfected press shown in my Patent No. 478,503, dated July 5, 1892, inasmuch as the beds are arranged one above the other and a pair of reciprocating impression-cylinders are operated backward and forward over said beds, each making an impression upon the web as they are traversed in both directions. In said patent, however, the beds are stationary, while those shown in this application reciprocate. The path of the web and the manner of feeding and deliver-

ing the web and of reversing it are practically the same as in the former invention, as shown in present application; but the means and operation for equalizing and spacing the web between the point of infeed and outfeed or delivery are different and must be to meet the new conditions of feed and tension occasioned by reciprocating both the cylinders and the type-beds, although the main synchronously-acting equalizing devices operating the looping-rollers U U of present application are the same as shown in my patent of July 11, 1893, No. 501,456, and operate in the same manner and to perform the same functions in the structure of the present application. The beds and cylinders in the present case are both traversed in opposite directions by four drivers, and the additional function of tensioning the web to meet the new requirements and conditions of feed, as required in the new combination, is performed by the vertical walking-rack rollers N and N', which are operated by small gears on the cylinder-shafts and which are one-fourth the pitch diameter of the cylinders, similar to the walking-racks of my Patent No. 332,139, of December 8, 1885. These take up and give back the web that is fed backward and forward by the reverse movements of the beds, and their action is compensated by the reciprocally-traveled coaxing-rollers M³ and M², which, as shown by drawings, are traveled by the beds, being journaled in a traveling frame P, which is bolted rigidly to the beds.

I am aware of many patents in this and foreign countries showing flat-bed type-printing web-presses variously employing web-feeds, reciprocating beds, and reciprocating cylinders, and I voluntarily disclaim all that is therein shown.

The invention is best defined in the claims, and the accompanying drawings illustrate what I consider the best form of apparatus now known to me embodying my invention.

Referring to said drawings, Figure 1 is a central longitudinal vertical section through such press. Fig. 2 is a side elevation thereof. Fig. 3 is a detail transverse vertical section through the same on line 3 3, Fig. 2.

The type-beds B B' are mounted and guided

between the side frames I of the press in any suitable manner, and the lower bed B' is reciprocated by means of pitmen G³, connected to wrist-pins on crank gear-wheels D³, keyed on 5 a shaft A³ at one end of the machine. Bed B is reciprocated by pitmen G', connected to wrist-pins on crank-gears D', keyed on a shaft A', parallel with but above shaft A³.

The cylinders C C', respectively coacting 10 with beds B B', are journaled in sliding carriages H H', guided on ways on the exterior of the frame. Carriage H is reciprocated by pitmen G, connected to wrist-pins on crank-wheels D, mounted on a shaft A, journaled 15 parallel with, above, and to the inner side of shaft A'. Carriages H' are reciprocated by pitmen G², connected to wrist-pins on crank-wheels D², keyed on a shaft A² below and parallel with shaft A. Gear D meshes with 20 gear D', and gear D² meshes with gears D' D³. Consequently the beds will be reciprocated alike in one direction, while the cylinders will be reciprocated alike, but in the opposite direction.

25 I do not consider my invention limited to any particular form of bed and cylinder moving devices or any particular arrangement thereof, only the beds and cylinders must both move in opposite directions and operate 30 upon a web.

Systems of inking-rollers l m n o are mounted in the carriages H H' at each side of the cylinders C C', as shown, and receive ink from fountains k, as will be readily comprehended 35 from the drawings.

L L' are web-infeed rolls, which may be driven by gears Q R S from gear D² or shaft A², as desired.

L² is a web-delivery roller, which may be 40 driven by gears d e from gear D. These parts may be driven as shown in my Patent No. 478,503, above referred to.

g represents coaxing-tapes running over rollers T T' and coacting with the feed-rolls, 45 and g' represents coaxing-tapes running over rolls T³ T² and coacting with the delivery-roller.

U u are web-looping rollers journaled in reciprocating plates V, which are operated by 50 pitmen b, connected to the front ends of levers W, pivoted at their rear ends Z on the main frame and lying athwart a shaft c, said levers having friction-rollers Y engaging cams X on said shaft, by which means the levers 55 W are vibrated and impart the desired reciprocating movements to loopers U u, and these parts are constructed and operated substantially as in my Patent No. 501,456, of July 11, 1893.

60 On the carriages H, at the side of the cylinder-shaft nearest the delivery, is a web-compensating device consisting of vertically-reciprocating rack-bars O, between which is journaled a roller N, the rack-teeth on said 65 bars meshing with small pinions P on the cylinder-shaft, as shown in Figs. 2 and 3. On carriage H', at the side of the cylinder-

shaft nearest the feed, is a web-compensating device consisting of vertically-reciprocating rack-bars O', carrying a roller N', the rack-teeth on bars O' meshing with pinions P' on the shaft of cylinder C'. Obviously, therefore, the rollers N N' will be raised and lowered alternately during the reciprocations of the cylinder and according to its movement. 75 The operation of said compensating devices is similar to that of the "walking-rack" movements in my Patent No. 332,139, of 1885, above mentioned.

p designates a frame attached to the beds 80 B B' and moving therewith, said frame extending to and projecting beyond the rear end of the side frames, and on said frame are mounted the web-reversing rollers M² M³, 85 the latter being preferably journaled in adjustable bearings q and constituting the "register-adjusting" roll.

M M' are guide-rollers mounted on carriages H' at opposite sides of cylinder C', and M⁴ M⁵ are guide-rollers mounted on carriages 90 H at opposite sides of cylinder C.

The web w from roll J is led in under a guide-roller K, between the feed-rolls T L L', up over looping-roller u, down under a stationary guide-roller K', forward under roller 95 M, up over compensating roller N', down under the cylinder C', over roller M', back under roller M², up over roller M³, forward over roller M⁴, under cylinder C, up over compensating roller N, down under roller M⁵, forward over a stationary roller K², down under looping-roller U, up to and through the delivery, and thence to a cutter.

Operation: The feed-rolls pay in and the delivery-rolls pay out enough paper for two 105 impressions for each complete reciprocation of beds C C'. During the time of taking impressions looping-rollers U u are raised at such speed that roller u takes up all the web fed in, and roller U gives off enough web 110 to supply the demand of the delivery. During the backward printing strokes of the beds (away from the feed) bed B' pulls forward a length of web equal to the travel of the bed during impression and bed B similarly 115 pulls back from the delivery a length of web equal to the travel of the bed during impression. The web demanded by bed B' in this backward movement is provided for by compensating roller N', which descends 120 (as the cylinder moves forward contrary to the bed) and gives off just enough from its loop to properly supply the demands of the bed and cylinder. Similarly compensating roller N descends and compensates the web 125 to the demands of bed B and cylinder C. The rolls M² M³, moving rearward with the beds and uniformly therewith, keep the web taut between the cylinders; otherwise there would be a slack in the web during the backward movement of the beds. During the forward movements of the beds (and backward movements of the cylinders) bed B feeds the web toward the delivery and bed B' feeds 130

web toward the feed. The demands of the beds and cylinders at this time are supplied by the forward movement of rolls $M^2 M^3$, and the slack which would otherwise accumulate

5 between cylinder C and the delivery and cylinder B' and the feed is taken up by the compensating rollers N N', which now ascend.

Obviously various changes could be made in the construction and arrangement of the 10 web-compensating mechanisms and the relative locations of the beds and cylinders and their operating devices, and I do not limit myself to the specific constructions and combinations of parts herein shown and described.

15 Having thus described my invention, what I claim as new, and desire to secure by Letters Patent thereon, is—

1. In a printing-press the combination of a 20 reciprocating bed, an oppositely-reciprocating cylinder, web-feeding mechanism, and a web-guide roller moving with the bed, and a web-compensating roller moving with the cylinder, substantially as described.

25 2. The combination of a pair of reciprocating beds, a pair of oppositely-reciprocating cylinders coacting with said beds, a web-feeding mechanism, and web-reversing guide-rollers between and movable with the beds, 30 and web-compensating rollers moving with the cylinders, substantially as and for the purpose described.

35 3. In a printing-press, the combination of a pair of reciprocating beds, and cylinders co-operating with said beds; and web feeding and delivery mechanism; with a web-compensating device between the feed and first printing mechanism; a second web-compensating device between the printing mechanisms; and a third web-compensating device 40 between the second printing mechanism, and the delivery, and a compensating roller beside and moving with each cylinder, substantially as set forth.

45 4. In a printing-press the combination of a pair of reciprocating beds, and a pair of reciprocating cylinders co-operating with said beds, a web-compensating device beside and moving with each cylinder; and web feeding 50 and delivery mechanism, with a looping-roller intermediate the feed and first moving com-

pensating device; and a web-looping roller intermediate the second moving compensating device and delivery, substantially as described.

55

5. In a printing-press the combination of a pair of reciprocating beds, and a pair of reciprocating cylinders co-operating with said beds, a web-compensating device beside and moving with each cylinder; and web feeding 60 and delivery mechanism, with a looping-roller intermediate the feed and first moving compensating device; and a web-looping roller intermediate the second moving compensating device and delivery, and web-reversing 65 rollers between and moving with the beds, all substantially as and for the purpose set forth.

6. The combination of a locomotive-cylinder with an oppositely-moving bed, and a 70 web-looping roller beside and moving with the cylinder, and means for moving said roller independently of, but during its travel with the cylinder, substantially as described.

7. The combination of a locomotive-cylinder with a web-looping roller beside and moving with the cylinder, and means for moving said roller independently of, but during its travel with the cylinder, with a bed moving oppositely to the cylinder, and means for feeding a web around said looping-roller and between the bed and cylinder, substantially as and for the purpose described.

8. The combination of oppositely-reciprocating beds and cylinders, web feeding and 85 delivery mechanism, a pair of connected looping-rollers between the feed and delivery, and the printing mechanisms, and cams and levers for operating said looping-rollers; with web-reversing rollers intermediate and moving with said beds; and web-compensating 90 rollers beside and traveling with each cylinder, and operated therefrom, substantially as and for the purpose set forth.

In testimony that I claim the foregoing as 95 my own I affix my signature in presence of two witnesses.

JOSEPH L. COX.
